UNITED STATES PATENT OFFICE.

EZEKIEL C. CONDIT, OF KANSAS CITY, MISSOURI.

URINAL.

SPECIFICATION forming part of Letters Patent No. 349,030, dated September 14, 1886.

Application filed March 16, 1886. Serial No. 195,451. (No model.)

To all whom it may concern:

Be it known that I, EZEKIEL C. CONDIT, of Kansas City, in the county of Jackson and State of Missouri, have invented certain new and useful Improvements in Urinals, of which 5 the following is a specification.

My present invention relates to urinals designed for use in school-houses or other public buildings, in connection with dry-closets 10 and ventilating-shafts; and the invention consists in the peculiar construction of the trough or urinal, as hereinafter more fully explained.

Figure 1 is a transverse vertical section of a portion of a building, showing my improved 15 urinal in position. Fig. 2 is a transverse horizontal section on the line $x-x$ of Fig. 1; and Figs. 3 and 4 are enlarged views of the trough detached, to illustrate its construction.

It has become customary of late to use dry- 20 closets in school-houses and similar large buildings, as fully set forth in Patent No. 318,884, the air from the various rooms of the building being conducted through the vault of the closet and from thence to the outer air 25 through a ventilating-shaft. As heretofore constructed the urinal used in connection with such dry-closets consisted simply of a metal trough running along the wall of a room, so arranged as to deliver its contents into the 30 ventilating-shaft near its base, or into the vault of the dry-closet as near the ventilating-shaft as convenient, no water being used to cleanse the trough or urinal, except as the same may be cleaned from time to time by the janitor or 35 person in charge of the building. In some cases this form of urinal is used independently of the dry-closet, it being arranged in such cases to deliver its contents directly into the ventilating-shaft. I have found in some cases 40 that these urinals after being used for some considerable time emit an unpleasant odor, which not only fills the small room in which they are located, but escapes therefrom into the halls and passage-ways, more or less, thus 45 tending to render the air within the building foul and unpleasant; and the object of my present invention is to prevent this.

In the drawings, A indicates the closet or room in which the urinal is located; B, the 50 vault of the dry-closet below; C, the foul-air duct, which delivers the warm and foul air from the various rooms of the building into

the vault, and D the ventilating-shaft connected to the vault B and extending out through and above the roof of the building, 55 and through which shaft a strong draft is maintained at all times.

I construct my improved urinal as shown in the several figures—that is to say, I first provide a trough, I, and then secure within it another trough, J, in such a manner as to leave a meniscus or crescent shaped space between them, as shown in cross-section in Fig. 3, the two troughs being joined or united along their edges in any suitable or convenient manner. 65 The inner trough, J, is provided with a series of perforations, e, which may consist of a single row along its center, as shown, or there may be, in addition to these others, arranged at intervals nearer the edges. The trough thus 70 constructed is secured at the proper height, somewhat inclined, as shown in Fig. 1, and has its delivery or lower end extended through the wall into the ventilating-shaft D. When thus arranged, the fluid delivered to the trough 75 J will pass through the perforations e into the space between the two, and will then flow along the trough I and pass from thence down into the base of shaft D, where, if desired, plaster-of-paris or other absorbent material 80 may be placed to be removed from time to time, the passing current of air, however, serving to evaporate it so soon that the use of an absorbent is not generally thought necessary. The draft of the ventilating-shaft will 85 create a suction through the trough I, or, rather, through the space between the two troughs, and to supply this the air will be drawn through the perforations e, and as it is thus drawn in it will of course be made to pass 90 over the surface of the trough J, more or less, and will gather up and carry with it any odor arising therefrom, and will also convey away all odor from within the trough I and the space above it, delivering the same into the 95 ventilating-shaft, from whence they are conveyed to the outer air. It will of course be understood that the space between the troughs at the end within the room will be closed, so as to compel the air to pass through the perforations from above. 100

It is obvious that this form of urinal may be used in connection with the dry-closet and be arranged to connect with the vault of the

same, or that it may be used independently of the dry-closet, provided there be a ventilating-shaft or other means for producing the necessary current or draft of air. By this 5 construction I am enabled to obviate the existence within the building of the disagreeable odor which might otherwise arise from urinals in which water is not kept running.

I am aware that it is common to construct 10 earthenware urinals and water-closets with openings and tubes for the connection of ventilating-pipes, and with a double bottom arranged to hold water, and thus form a trap to 15 prevent the entrance of sewer-gas, and therefore I do not claim such; but,

Having fully described my invention and the manner of using the same, what I do claim is—

1. A urinal consisting of the imperforate trough I and the perforated trough J, the two 20 being arranged in relation to each other substantially as shown and described.

2. In combination with the ventilating-shaft D, the compound or double trough J I, constructed and arranged to operate substantially 25 as and for the purpose set forth.

EZEKIEL C. CONDIT.
